United States Patent Office

Des. 213,182
Patented Jan. 14, 1969

213,182

NOVELTY VEHICLE ACCESSORY

James N. Colman, 3527 Pacific, St. Joseph, Mo. 64507

Filed Apr. 1, 1968, Ser. No. 11,249

Term of patent 14 years

U.S. Cl. D14—6
Int. Cl. D12—14

Fig.1.

Fig.2.

Fig.3.

FIG. 1 is an elevational view of the accessory showing the same applied to an automobile aerial, the aerial being fragmentarily shown in dotted lines for purposes of illustration;

FIG. 2 is an elevational view thereof showing the same in a different position; and

FIG. 3 is a top plan view of the novelty vehicle accessory.

I claim:

The ornamental design for a novelty vehicle accessory, as shown and described.
